(57) **CLAIM**

The ornamental design for a side panel of a road roller, as shown and described.

DESCRIPTION

FIG. 1 is a front left perspective view of a side panel for a road roller, showing my design;

FIG. 2 is a rear right perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof; and,

FIG. 9 is a front left perspective view of the side panel for a road roller in use on a road roller.

The design also includes a second embodiment that is mirror symmetrical to the illustrated design and is therefore not separately illustrated.

The broken line showing of a road roller in FIG. 9 is included for the purpose of illustrating environmental structure only and forms no part of the claimed design.
